UNITED STATES PATENT OFFICE.

NICOLAS GHERASSIMOFF, OF ST. PETERSBURG, RUSSIA.

APPARATUS FOR PREVENTING COLLISIONS AT SEA.

SPECIFICATION forming part of Letters Patent No. 693,855, dated February 25, 1902.

Application filed June 20, 1899. Serial No. 721,253. (No model.)

To all whom it may concern:

Be it known that I, NICOLAS GHERASSIMOFF, military engineer, a subject of His Majesty the Czar of Russia, residing at 16 Rue des 5 Officiers, St. Petersburg, Russia, have invented a certain new and useful Improvement in Apparatus for Preventing Collisions at Sea, (for which I have made applications for Letters Patent in France under date of December 30, 1898; in Great Britain under date of January 10, 1899; in Germany under date of January 30, 1899, and in Russia under date of February 2, 1899, [new style];) and I do hereby declare that the following is a full, 15 clear, and exact specification of the same.

A disaster at sea is almost always the result of a collision between the ship and some moving or stationary body which is situated in the path of the said ship, either at the surface or at a depth less than the draft of the ship and which is not perceived in time, or it is due to an error made in estimating the position of the said body and the course of its deviation.

25 My invention has for its object the provision of means whereby the collisions referred to can be effectually avoided, and I attain this object through the medium of appliances the organization of which is such as to enable them to perform their function at all times and under all conditions of weather and sea and irrespective of the vigilance of the commanding officer of the ship met with and so as to apprise the officer of the ship equipped 30 with said appliances of an obstruction ahead, whether stationary or in motion, whether in the direct course of the ship or moving across its bows or toward his ship at an angle to its course, and to indicate to said officer the 35 course he should take to avoid collision. Furthermore, the construction and operation of said appliances are such as to apprise the officer in command of the ship liable to come into collision with the one equipped with said 40 appliances of the presence and position and course of the last-named ship.

One of the essential features of my invention lies in the use of contact devices which practically perform the function of "feelers" 45 and will hereinafter be referred to as such. These feelers move in advance of and at substantially the same rate of speed as the ship

they protect and at such a depth under water as not to be materially interfered with by the waves and so as to come in contact with any obstruction at a depth less than the draft of the ship. The feelers are so disposed and connected as to contact with or indicate an obstruction, stationary or floating beneath the surface or in motion, whether in the direct course of the ship or on one or the other side thereof or moving toward the ship in its direct course or at an angle thereto. The deviation of the feelers from a straight course, due to their collision with an obstruction in 65 their path or to the action of such obstruction on their connecting devices, is made use of to indicate the course the vessel is to take to avoid the obstruction and, in case the latter is a ship, to apprise the officer in command, through the blow or impact and through the medium of a suitable signal, of the presence of another ship and the position and course of the same.

Other features of my invention lie in means 70 for determining at all times the position of the feelers relatively to the ship and to vary their course in accordance with variations in the course of the ship.

That my invention may be fully understood, 75 I will describe the same in detail, reference being had to the accompanying drawings, in which—

Figure 1 shows the general arrangement of the feelers in plan. Fig. 2 shows the same arrangement, but in profile, the vertical distances being increased ten times. Figs. 3, 4, and 5 illustrate the general construction of the middle feeler, of which Fig. 3 is a vertical section corresponding to the line 3.3 of Fig. 4; Fig. 4, 80 a horizontal section corresponding to the line 4.4 of Fig. 3, and Fig. 5 a vertical section corresponding to the line 5.5 of Fig. 4; and Figs. 6 and 7 are two vertical and horizontal sections, drawn to a larger scale, of the same 85 feeler and corresponding, respectively, to the lines 6.6 and 7.7. Fig. 8 illustrates the arrangement of the apparatus for indicating the deviations of the middle feeler. Fig. 9 is a vertical section corresponding to the line 9.9 90 of Fig. 10, illustrating the construction of a side feeler; and Fig. 10 is a horizontal section of the same feeler on the line 10.10 of Fig. 9. Fig. 11 illustrates, to a larger scale, the ar- 95

angement of the apparatus for indicating the deviations of the side feeler. Fig. 12 is a plan of the arrangement on the ship of a graduated scale with a telescope for verifying or ascertaining the position of the conducting-cable, and Fig. 13 is a diagram of the electric circuits.

It will of course be understood that the feelers 1, 2, and 3, Fig. 1, will be connected with the ship, as hereinafter described, so as to move at a sufficient distance ahead to give the commander ample time to change his course the moment the danger-signal is given apprising him of the presence of a shoal, rock, or other vessel or of another ship either in his course or moving toward him at an angle thereto. The said feelers are not only connected together by electric cables $Z Z' Z''$, which are united at a suitable point W , and thence carried together or as a single cable to the ship, but they are also connected together by ordinary cables $c c'$ in such manner as that said cables will form together a square, two of the angles of which will lie in the plane of the longitudinal axis of the ship, or, in other words, in the course thereof, and the other two in planes diverging from said longitudinal axis of the ship or its course. Inasmuch as the depth-indicators are also connected by like cables $M M' M'' M'''$, it is obvious that should a ship V cross the course of the ship A at a point intermediate of the feelers 1, 2, Fig. 1, or intermediate of the feelers 2, 3, or intermediate of the latter feelers and the point W , or intermediate of the point W and the feeler 1, such vessel will strike one set of cables, as $c M$, Fig. 1, deflect the same, as shown in dotted lines, and thereby cause an audible signal to be given on board ship, this being also the case should any one of the feelers 1, 2, 3, or the complementary feeler or depth-indicator Q thereof collide with an obstruction, as hereinafter described. Thus, for instance, if a vessel V , Fig. 1, were to cross the path of vessel A between feelers 1 and 2 such vessel would collide with and deflect the cables $c N$, connecting said feelers and their depth-indicators, thereby producing a signal on board vessel A , which indicates to the commander that the obstruction is on his left, and he will then change his course to the right, as along the dotted arc 30-90. At the same time the commander of vessel V will be advised of the obstruction ahead, not only by the impact or collision with the feeler-cables $c N$, but also by visible signal, which will indicate to him the position of and course taken by vessel A , so that he, too, may change his course in an opposite direction, or to the left. Of course should the collision of a vessel take place between feelers 2, 1, or 3 and point W or between the latter point and feeler 1 the commanders of the two vessels would then change their courses accordingly, so as to avoid a collision.

As shown in Figs. 3 to 7 and 9 and 10, each feeler comprises a casing having the shape that

will offer the least resistance to movement in water. In this casing there are situated electric motors E , which transmit motion to a screw-propeller H . These electric motors must be sufficiently powerful to enable them to overcome not only the resistance to the motion of the feeler with its accessories, but also to drag their conducting-cable along, and consequently to exert a pull of a given force upon the ship. Consequently the conducting-cables $Z Z' Z''$, Fig. 1, in addition to being designed to conduct the electric current to the electric motors E from the dynamo placed on the ship, have also to act as tow-ropes stretched from the feelers. The middle feeler 2, Figs. 3 to 8, is provided with a fixed rudder G , which is arranged in the vertical plane passing through its axis and which will maintain the feeler always in the direction of the movement of the entire apparatus—i. e., in the position in which it will meet with the minimum resistance from the water. The feeler is connected to its framing b by means of vertical trunnions t and t' , which pass through its center and which can rotate freely in bearings of the framing b . A special apparatus, hereinafter described, enables the feeler to be affixed or rendered immovable at the desired moment in relation to its framing in order to cause them to turn together. The conducting-cable Z is permanently connected to the framing b , so that if the power of the screw-propeller H of the feeler alone comes into operation the conductor Z will lie in a plane parallel with the longitudinal axis of the feeler and the framing b will be at right angles to it. If the conductor Z changes its direction from any cause, it will cause the framing to turn without affecting the position of the feeler. Consequently when the accidental force ceases to act the conductor will resume its original position.

In order to change the position of the feelers, the middle feeler is provided with an apparatus that enables it to be rendered immovable in its framing and bringing it back into a position perpendicular to the latter, and the propelling force of the side feelers is capable of being varied. As shown in Figs. 4 and 7, the framing b has two side pieces f and f' , which limit the oscillations of the feeler to about ten degrees each side and upon which bear the heads of the screws v and v' when these screws are moved into their extreme positions. The screws work in nuts l and l' by means of their central screw-threaded portion. At their inner ends the screws carry rollers or disks g and g' , which are in slight frictional contact with the surface of an iron wheel F , fixed on an extension of the screw-propeller shaft, which is made of a diamagnetic metal. On the other side of the wheel F there is placed a coil B , which receives the current through special conductors. (Shown in Figs. 6 and 7.)

In normal circumstances the motion of the wheel F is unable to move the rollers g and

g' , which are held back by springs y and y' ; but when the coil B receives current the adhesion between the magnetized wheel F and the rollers g and g' becomes so great that the screws v and v' and their heads are turned until both the screws have reached their extreme positions, which are indicated by dotted lines in Fig. 7. When the current of the coil is interrupted, the springs y and y' cause the screws to revolve and return to their original positions. It will be seen from Fig. 1 that the feelers 1 and 3 have in relation to the feeler 2 oblique positions, in which they are maintained by the rudders G, the simple cables c c' , and the conducting-cables $Z' Z''$, which connect them to the feeler 2 and to the ship A.

In consequence of the oblique position of the feelers there exist normal components R_1 and R_2 , which are equal to the propelling force F_1 and F_2 multiplied by the cosine of the angle and between the direction of propulsion and the line normal to the movement of the entire apparatus. In normal conditions $F_1 = F_2$, $\alpha = \alpha_1$, and $R_1 = R_2$; but when the meeting with any object increases α , as in Fig. 1, then equilibrium no longer exists, R_1 becomes less than R_2 , and consequently the feelers will receive a movement in the direction opposed to the obstacle. The ship must follow them. When, on the contrary, it is desired to change the direction of the entire apparatus, the desired movement can always be given by making F_1 greater or smaller than F_2 , while rendering the middle feeler immovable.

In order to give the desired position to the entire apparatus, to measure the angle of inclination, and to ascertain or verify the position of the apparatus in relation to the vessel, I arrange on the vessel at the point of attachment of the conducting-cable Z of the middle feeler 2 a graduated scale P, Fig. 12, of which the zero-mark coincides with the point of attachment of the cable, which is situated in the center line of the ship. Upon the scale P and perpendicular thereto there is arranged a telescope S, which is capable of being moved, while always retaining its respective or relative position or its perpendicularity to the scale P.

Upon the conducting-cable Z there is arranged a small electric lamp q, Fig. 12, situated at a determined distance from the scale P. It is obvious that the angle of inclination of the conducting-cable Z—that is to say, of the entire apparatus—can be measured with the aid of this appliance.

Having now shown how the position of the feelers can be controlled and ascertained, I shall now proceed to describe the warning arrangements.

All the feelers must indicate places of insufficient depth. Further, the feeler 1 will indicate inclination to the right, feeler 3 will indicate inclination to the left, and feeler 2 will indicate inclination to the right and to

the left and the contact of its bow against the obstacle. In order to render the movement of the feelers more steady, they are entirely immersed in the water at about one-half of the draft of water of the ship, and the point of attachment of the conducting-cables $Z' Z''$ and of the simple cables c and c' must correspond with the conditions of equilibrium of the forces that come into operation. In order that the feeler may indicate to the vessel met with the position of the ship that is following and for the purpose of balancing the excess of the weight, each feeler is provided at the surface of the water with a buoy u, Figs. 3 and 9, that carries an electric lamp having a color which corresponds to the position of the feeler in relation to the ship. For the purpose of offering the least resistance during motion the buoy u is made capable of turning on an upright arm K, rigidly connected to the framing b. Cables (of which M M' are shown in Figs. 3 and 9) connect the arms K together in order that the apparatus may give warning of floating bodies that are situated at a depth such as will render their meeting dangerous for the ship.

For the purpose of indicating shoals the feelers are provided with pendent levers D' D'', Figs. 3, 6, and 9, each carrying at its end a weight Q, which is situated at the depth of the draft of the vessel, with the usual clearance, and the inclination of which in its universal joint J moves the contact-piece T toward one of the springs r, as will be seen from Figs. 6 and 7. Then the current of a bell, as B' or B'', Fig. 13, which are situated on board ship, will be closed and the sound will give an indication of the obstacle. As the pendent levers D' D'' are connected together by cables, of which M' M'' are shown, any intermediate obstacles will also be indicated, but in this case by two bells.

As to the middle feeler 2, a bell B², Fig. 13, for indicating depth will also be set into operation or when the bow of the said feeler collides with any obstacle. In the latter case the bent bar i will move the spring r toward the contact T, and the electric circuit will be closed. Springs j and j', Figs. 9, 3, and 6, are designed to retain the bar i and pendent levers D' D'' in their original normal positions, respectively.

In order to indicate the inclination or deviation of the framing of the feeler 2 in relation to the latter, the rudder G of the feeler is provided with a lever l, Figs. 4 and 8, which is bent into the form of an arc of a circle and the ends of which are provided with pistons p and p', that work in tubes, which are rigidly connected to the framing and which contain conductors m and m', that act as weak springs. The deviation of the framing displaces the pistons p and p' and closes the circuit at one side or the other and causes one of two bells B²² or B⁴², Fig. 13, to ring on board ship, according as the deviation or inclination of the frame is to the left or right.

The side feelers 1 and 3 are different from the feeler 2 in that the position of the rudder G, Fig. 10, that produces the oblique motion, is inclined. Further, the framing is in one piece with the feeler and the warning apparatus has only to indicate the decrease of the angle comprised between the conductor Z' and the cable c. From Figs. 10 and 11 it will be seen that the principle of the apparatus is the same as hereinbefore described; but the possible displacements of the pistons q' and q'' in relation to the tubes s are very small.

The conducting-cables Z Z' Z'' are supported in the middle by a buoy W, Fig. 1, in order to prevent them from dipping so much as they would without such a support and in order to enable the conducting-cables Z' and Z'' to be inclined according to requirement.

The conducting-cables must comprise conductors for the electric motors, with branches for the lamps of the buoys, and conductors for the depth-indicating bells; also, the conducting-cable Z must comprise the conductors of two bells and of the immobilizing device f f' g g' v v' y y', Fig. 7, and the conducting-cables Z' and Z'' must each comprise a conductor for one bell. There are thus on board ship three depth-indicator bells B' B² B³, one for each feeler 1, 2, and 3, respectively, the bell B² also indicating collisions of feeler 2 with an obstruction in its path. Furthermore, there is a deviation-indicator bell B²¹ and B²³ for the feelers 1 and 3 and, as aforesaid, two deviation or inclination indicator bells B²² and B²⁴ for the middle feeler 2. (See Fig. 13.) This is quite sufficient for the purpose of indicating the location of any obstacle in the path of the ship A, as well as the direction of deviation of the feelers.

I will now briefly describe the electric circuits, reference being had to said Fig. 13, wherein the feelers 1, 2, and 3 and the fore part of the ship A are shown in dotted lines, D⁰ indicating the source of electricity on board said ship, as a dynamo 4, being the main return-lead, the positive pole of said dynamo being connected with rheostats 5' 5² 5³ by leads G G' G'', the rheostat 5' being connected with the pistons q' q'' of the feeler l through lead z', and branch z^x z² being the return-lead connected with the deviation-indicator bell B²¹ on board ship and the latter with the main return-lead through wire z³. The feeder or lead z' also supplies power to the dynamo E of said feeler l, the pole of said dynamo being connected with the main return-lead 4 through lead z⁴. A branch circuit z⁵ of feeder z' supplies current to the lamp of buoy u of feeler l, and said feeler is connected through wire z⁶ with the contact device T^r for the depth-indicator bell B' of said feeler, z⁷ being the return-lead connected with depth-indicator bell B' on board ship, which bell is connected with the main return-lead 4 through wire z⁸, the wires z', z², z⁴, and z⁷ being united into the cable Z'. The same arrangement of conductors prevails as re-

gards feeler 3, the rheostat 5³ being connected by feeder or lead z¹¹ with the feeler-motor E, z¹¹ being the return-lead connected with main return-lead 4, the lamp of buoy u being in a branch circuit z⁶¹ from said feeder z¹¹, which also supplies current to the contact device T^r through lead z⁶¹, while the return-lead z¹¹ of said contact device is connected to the depth-indicator bell B³ on board ship, said bell being connected with main return-lead 4 through lead z⁸¹. Finally feeder z¹¹ supplies current to the deviation contact devices q' q¹¹ s s, z²¹ being the return-lead through deviation-indicator bell B²³, said bell being connected with the main return-lead 4 through wire z³³, the leads z¹¹, z²¹, z¹¹, and z²¹ being united into the cable Z¹¹. The feeler 2 has the same electrical connections as the feelers 1 and 3, with this exception that there are two deviation-indicator bells B²² B²⁴. The + pole of the dynamo D⁰ is connected by lead 6³ with rheostat 5², as stated above, and the latter with the + pole of the motor E of said feeler 2 through feeder or lead z³¹, in a branch z^x of which is included the lamp of the buoy u, and a branch z⁶¹ supplies current to the contact device T^r of the depth and collision appliances D' i, the return-lead z⁸¹ of which is connected with the depth and collision indicator bell B² on board ship, said bell being connected with the main return-lead 4 through wire z⁹¹. The main feeder 6³ is also connected with the rheostat 5⁴ and the latter with the + pole of the coil B of immobilizing-wheel F through lead z⁵¹, the return-lead z⁵² being connected with the main return-lead 4. Finally, the feeder z³¹ supplies current to the deviation-pistons or their connecting-rod l through branch lead z¹². The return-leads z¹³ z¹⁴, respectively connected with the contact springs or conductors m and m', as hereinbefore described, are connected with the left and right hand deviation-indicator bells B²² B²⁴ and the latter with the main return-lead 4 through leads z¹⁵ and z¹⁶, respectively. In leads z³¹, z⁸¹, z⁶¹, z⁵³, z¹³, and z¹⁴ are united into the cable Z, while said cable and the cables Z' and Z¹¹ are united into a common cable at a point some distance from ship A, at or near which point is attached the buoy W.

The manipulation and operation of the electrically-actuated appliances will be fully understood from the above description and from the preceding detailed description and therefore does not need further amplification, the flow of the currents being indicated in Fig. 13 by arrow-heads.

If required, it would not be difficult to produce also an automatic deviation of the rudder of the ship in accordance with the position of the feelers; but the apparatus would be more complicated. The apparatus can, on the other hand, be simplified in the case of ships that do not travel fast and whose turning circle is small by connecting the middle feeler rigidly to its framing, and conse-

5 quently dispensing with the immobilizing apparatus and the left and right hand bells. It will still be possible to check or ascertain the position of the apparatus with the aid of the telescope. There is no certainty that such an apparatus will always indicate the path to be followed; but it will always be useful for warning the vessels that are met with.

10 I shall not enter into the details of the warning devices on the ship, because this depends very much on local conditions and will also not offer any difficulty, and for the same reason I shall not give any calculations. I may also state that it should be possible to regulate within wide limits the intensity of the current that is sent to the electric motors for the purpose of varying the speed of the latter, and a windlass should be provided for the purpose of drawing back or taking up the 15 feelers when their services are no longer required.

20 It is obvious that the condition of the atmosphere cannot have any influence and that the condition of the sea can only have an influence upon the mode of operation of the apparatus, because although 25 large waves may interfere to a slight extent with the traveling of the feelers the respective position of the feelers cannot be changed, either by these waves or by rolling or pitch- 30 ing.

35 I have thus attempted to show in this specification that the proper working of the herein-described apparatus will give alone to the ship fitted therewith a complete guarantee 40 against collisions with stationary obstacles and also with vessels fitted with feelers or traveling at the speed limited by the international convention. My apparatus thus complies with all the conditions mentioned at the commencement of the present specification, and everything tends to the belief that with antennae of sufficient length, which can be 45 guided at will, and are, so to speak, intelligent, a ship will have a safety in traveling that has been hitherto unknown.

Having now described my invention, what I claim, and desire to secure by Letters Patent, is—

50 1. The combination with a ship, of a feeler, consisting of an electrically-propelled buoyant body connected with said ship, collision and depth indicating appliances connected with said body, an electrically-operated collision and shoal-water indicator on board ship, controlled by the aforesaid collision and depth indicating appliances, an electric circuit including said appliances and indicator and means for supplying current to the 55 feeler-propeller from aboard ship, for the purpose set forth.

60 2. The combination with a ship, of a feeler, consisting of an electrically-propelled submerged buoyant body a float connected with 65 said body, an electrically-operated visible signal carried by said float, collision and depth indicating appliances likewise connected with

the body, a collision and shoal-water indicator on board ship controlled by said appliances, an electric circuit including said signal, the collision and depth indicating appliances and the collision and shoal-water indicator, and means for supplying current to the feeler-propeller, for the purpose set forth.

3. The combination with a ship, of a feeler, 70 consisting of an electrically-propelled submerged buoyant body a float connected with said body, an electrically-operated visible signal carried by said float, collision and depth indicating appliances likewise connected with 80 the body, a collision and shoal-water indicator on board ship controlled by said appliances, an electric circuit including said signal, the collision and depth indicating appliances and the collision and shoal-water indicator, and means for supplying current to the 85 feeler-propeller, the circuit-leads being united into a cable serving to connect the feeler with the ship, for the purpose set forth.

4. The combination with a ship, of a submerged feeler flexibly connected with and moving in advance of said ship, a depth-indicator flexibly connected with and depending from said feeler, a float likewise connected with said feeler, a signaling device connected 90 with the float, a like device on board ship, and means actuating the last-named signaling device when the feeler or depth-indicator collides with an obstruction, for the purpose 95 set forth.

5. The combination with a ship, of a submerged feeler flexibly connected with and moving in advance of said ship, means for steering the feeler, a depth-indicator flexibly connected therewith and depending therefrom, a float-rod rigidly secured to the feeler, a float mounted to revolve on said rod, a signaling device connected with said float, a like device on board ship, and means actuating the last-named signaling device when the 100 feeler or the depth-indicator collides with an obstruction, for the purpose set forth.

6. The combination with a self-propelling feeler serving the purposes specified and comprising a buoyant body of a frame in which 115 said feeler is mounted to rotate on vertical journals, and means for limiting the amplitude of rotation, for the purpose set forth.

7. The combination with a self-propelling feeler serving the purposes specified and comprising a buoyant body, of a frame in which 120 said feeler is mounted to revolve on vertical journals, and means for locking the feeler against rotation, for the purpose set forth.

8. The combination with a ship, a feeler 125 serving the purposes specified, and a frame in which said feeler is mounted to revolve on vertical journals; of means indicating on board ship the angle of displacement of the feeler on its journals, for the purpose set forth.

9. The combination with a ship, a feeler 130 serving the purposes specified, a frame in which said feeler is mounted to revolve on vertical journals, and a rudder for said feeler;

- of appliances controlled by said rudder and indicating on board ship the inclination of the feeler relatively to its frame, substantially as and for the purpose set forth.
- 5 10. The combination with a ship, a feeler serving the purposes specified, a frame in which said feeler is mounted to revolve on vertical journals, and a rudder for the feeler; of electrically-operated appliances controlled 70 by said rudder, indicating on board ship the inclination of the feeler relatively to its frame, for the purpose set forth.
11. The combination with a ship, a feeler serving the purposes specified, and a frame in which said feeler is mounted to revolve on vertical journals; of electrically-operated appliances for moving the feeler back into a normal position when displaced on its journals, and for locking said feeler against such 75 displacement, and means on board ship for controlling the operation of said appliances, for the purpose set forth.
12. The combination with a ship, a feeler, a rudder rigidly secured thereto, a frame in which said feeler is mounted to revolve on vertical journals, and means controlled by the rudder indicating on board ship the displacement of the feeler on its journals relatively to its frame, or vice versa; of electrically-operated appliances for moving the feeler back into its normal position when displaced, and a device on board ship for controlling the 80 operation of said appliances, for the purpose set forth.
13. The combination with a ship, three self-propelling feelers, a parallelogram of flexible connections with the feelers at three of the angles and a flexible connection connecting the fourth angle with the ship at the bow, of 85 means for indicating on board ship the deviation in one direction of two of the feelers and the deviation in either direction of the third or leading feeler, and means controllable from aboard ship for correcting such deviations, for the purpose set forth.
14. The combination with a ship, three submerged self-propelling feelers, a luminous floating signal for each feeler, a parallelogram of flexible connections with the feelers at three of the angles, a like connection connecting the fourth angle with the bow of the ship, of means for indicating on board ship deviations of the feelers from their courses, means controllable from aboard ship for correcting such deviations and for directing the course 90 of the feelers, for the purpose set forth.
15. The combination with a ship, three self-propelling feelers, a parallelogram of flexible connections with the feelers at three of the angles, and a flexible connection connecting the fourth angle with the ship at the bow; of means controllable from on board ship, maintaining the feeler at the forward angle in the ship's course, the other two feelers connected 95 to take courses diverging from said ship's course controllable from on board ship and controlling the speed of the feelers, and ap- 100 pliances causing a signal to be given on board when one of the feelers or a connection between two of them meets with an obstruction, for the purpose set forth.
16. The combination with a ship, three self-propelling feelers, a depth-indicator flexibly connected with and depending from each of said feelers, a parallelogram of flexible connections with the feelers at three of the angles thereof, a like connection connecting the fourth angle to the ship at the bow, and flexible connections between the depth-indicators; of means controllable from aboard ship maintaining the feeler at the forward angle in the ship's course, means for maintaining the other two feelers in courses diverging from the ship's course, means controllable from aboard ship controlling the speed of the feelers, and 105 means causing a signal or signals to be given on board when a feeler or depth-indicator or a connection between them meets with an obstruction, for the purpose set forth.
17. The combination with a ship, three self-propelling feelers, a depth-indicator flexibly connected with and depending from each feeler, a float-rod rigidly secured to each of said feelers, a float mounted to revolve on the respective rods a signaling device connected with each float, a parallelogram of flexible connections with the feelers at three of the angles thereof, a like connection connecting the fourth angle with the ship at the bow, and similar connections between the depth-indicators; of means controllable from aboard ship for maintaining the feeler at the forward angle of the parallelogram in the ship's course, means maintaining the other two feelers in courses diverging from the ship's course, means controllable from aboard ship controlling the speed of the feelers, means causing a signal or signals to be given aboard ship when a feeler or depth-indicator or a connection between two feelers or depth-indicators 110 meets with an obstruction, and means simultaneously operating the float signaling device, for the purpose set forth.
18. The combination with a ship, three self-propelling feelers a parallelogram of flexible 115 connections with the feelers at three of the angles thereof, a like connection connecting the fourth angle with the ship at the bow, means maintaining the feeler at the forward angle in the ship's course, and the other two 120 feelers in courses diverging from said ship's course, appliances controlled by deviations of the feelers from their respective courses causing a signal or signals to be given aboard ship, and appliances controllable from aboard 125 ship causing the feelers to resume their normal courses, for the purpose set forth.
19. The combination with a ship, three self-propelling feelers, a parallelogram of flexible connections with the feelers at three of the 130 angles thereof, a like connection connecting the fourth angle with the ship at the bow, means maintaining the feeler at the forward angle in the ship's course, and the other two

feelers in courses diverging from said ship's course, appliances controlled by deviations of the feelers from their respective courses causing a signal or signals to be given aboard ship, and appliances controllable from aboard ship acting on the feeler at the said forward angle to bring the same into its normal course and therethrough the other two feelers, for the purpose set forth.

20. The combination with a ship, of appliances substantially such as described, comprising three feelers connected together and

with the ship as set forth; of means on board ship for determining the proper position of the feelers relatively to said ship, means controllable from aboard ship and controlling the advance feeler for bringing the latter and therethrough the other feelers into their proper operative positions relatively to the ship, for the purposes set forth.

NICOLAS GHERASSIMOFF.
